DEVICE FOR CONVERTING BOTTLES, JUGS,
VASES OR THE LIKE INTO LAMPS

Heinz S. Edelmann, New York, N. Y.

Application February 13, 1956, Serial No. 40,124

Term of patent 3½ years

(Cl. D48—20)

Fig. 1 is a perspective view of a device for converting bottles, jugs, vases or the like into lamps showing my new design, the broken lines representing a bottle being for illustrative purposes only;

Fig. 2 is a bottom plan view thereof; and
Fig. 3 is a side elevation view.

I claim:

The ornamental design for a device for converting bottles, jugs, vases or the like into lamps, as shown and described.
